UNITED STATES PATENT OFFICE.

TALBOT G. MARTIN, OF CHICAGO, ILLINOIS, ASSIGNOR, BY MESNE ASSIGNMENTS, TO
 AUTOMATIC ELECTRIC INC., OF CHICAGO, ILLINOIS, A CORPORATION OF DELA-
 WARE.

AUTOMATIC TELEPHONE SYSTEM.

Application filed June 30, 1920, Serial No. 392,943. Renewed June 25, 1926.

My invention relates in general to automatic telephone systems, but is more especially concerned with the trunking arrangements in such systems; and the object of the invention may be stated to be, broadly, the design of a new and improved trunking system for an automatic telephone exchange, or system, in which connections are established through the medium of serially related automatic switches, and in which one of the switches in a series belonging to a major group of the system may be omitted for the sake of economy at the initial installation without interfering with the use of a complete numbering system laid out in accordance with the ultimate capacity.

In order to carry out the general object of the invention as above set forth, I have designed a special selector switch which may be called a combination selector and digit absorber, a digit absorber selector, or simply a drop back selector.

This switch releases or drops back when a certain digit is called and in effect eliminates one of the digits in the telephone numbers of a certain major group so that the lines in such group may be reached by means of a smaller series of switches than the lines in other groups.

In view of the above it will be understood that the invention resides in the new trunking arrangement, and in the special means, the drop back selector, which is used to render this trunking arrangement practicable, and these features will now be described more fully, reference being had to the accompanying drawings.

In the drawings, comprising but a single sheet, Fig. 1 is a schematic diagram of the trunking system; while Fig. 2 is an ordinary circuit diagram of the drop back selector.

Referring to Fig. 1, this diagram shows a portion of the trunking system in an automatic telephone system having a capacity of 100,000 lines, and using the well known Strowger vertical and rotary switches operated according to the two wire system of control. In a system of this size the lines are usually distributed among a plurality of different offices, and the first selectors, which are the switches which respond to the first digits in called telephone numbers, may function as office selectors. Since there are ten levels in a selector switch there may con-

veniently be ten different offices, and when a calling subscriber operates his dial to call a desired number, the first digit will operate a first selector to select a trunk line leading to the proper office, and the remaining digits will operate second and third selectors and a connector in the selected office to complete the connection. Thus, referring to Fig. 1, suppose the subscriber at substation A desires to call the subscriber at substation A². When the receiver is removed the individual line switch or trunk selector C is operated automatically to select a trunk line extending to an idle first selector, such as the selector D, for example. The calling device is now operated in accordance with the number of substation A², and when the first digit is called, the proper office is selected by raising the wipers of selector D until they stand opposite the level assigned to such office. The automatic rotary movement of the selector is now initiated and a trunk line is selected extending to an idle second selector in the distant office, as the second selector E, for example. Then the calling device is operated for the remaining digits, and the selector E, a third selector which may be the selector F', and a connector which may be the connector H' are operated successively to complete the connection to the desired line.

The above described trunking arrangement will be recognized as the well known decimal or percentage trunking system which is in use in practically all automatic exchanges. Having paved the way, so to speak, by describing what is old, I will now proceed to the new features. In laying out a telephone system it is desirable to make the division into offices at the start and to locate the offices throughout the territory served in accordance with the best estimates of future growth. It is not meant by this that all offices are necessarily installed at once for some sections where a large future growth is probable may not be built up at all at the time, or very sparsely; but what is meant is that an intelligent plan is devised based on a study of the probabilities. Those offices are installed which are required for immediate needs and others may be reserved for use in sections which may be built up in the future. When such a plan is followed certain blocks of telephone numbers (which of course correspond to the

offices) are set apart for use in each section, and additions may be made from time to time without changing the trunking plan originally adopted or the telephone numbers originally assigned. The desirable feature that is to be retained at all events, if possible, is that of so arranging the trunking at the start that additions may be installed from time to time without rearrangement of the trunking or changing of telephone numbers. Heretofore, as far as applicant knows to attain this object it was necessary to install a complete series of switches comprising first, second, and third 10 selectors and connectors in each office as soon as such office was started, or initially installed, even though there might be only a few hundred lines served by such office at the start. These lines would have to be 15 given the regular five digit telephone numbers in accordance with the general development plan, and this would require the full quota of switches, as stated.

Now it is quite generally true that when 20 an outlying office is first installed it will serve at the start but a small fraction of its total ultimate capacity. For example, an office may be installed to take care of a present total of 500 lines, located in a district which, although marked for a large ultimate growth, may nevertheless remain below the 1000 line figure for several years. It will be evident that as long as the size 25 of the office does not exceed 1000 lines, only second selectors and connectors would be required so far as establishing connections are concerned; but since as stated, it is desired to assign five digit telephone numbers 30 at the start, third selectors would ordinarily have to be installed also in order to preserve the general five digit numbering scheme.

It is to meet this situation that I have devised the digit absorber or drop back selector. By the use of this switch, which is 35 used as a first selector, I am able to omit the third selectors in those offices where they are not required and still preserve the five digit numbering system. This can be most clearly explained by reference to the drawing, Fig. 40 1. The upper series of switches comprising the second selector F and the connector H are assumed to be located in an office having less than 1000 lines connected thereto, and this office is accessible from the third 45 level of the office selectors. The first digit in the telephone numbers of all lines connected to this office is therefore the digit 3; and the numbers when the office is entirely 50 filled up will run from 30,000 to 39,999. 55 That is, there are ten different thousands, 30,000, 31,000, 32,000, 33,000, etc., which will be available ultimately when the full quota 60 of switches are installed. For the present, however, the third selectors are omitted, 65 drop back first selectors are used, and only

the 33,000 block of telephone numbers are used.

With this arrangement the process of establishing a connection between substation A and A' may be explained, the number of the latter substation being assumed to be 33456. When the receiver is removed the calling line is of course connected with an idle first selector, such as the selector D. The first selectors, as before stated, are of the drop back type, and are so designed that when operated they at once restore to normal, or drop back, provided the digit called is the digit corresponding to an office having no third selectors. When the digit 3 is 70 called therefore the selector D is raised to the third level and then immediately releases. When the release takes place a relay is automatically locked up which alters the selector circuit so that if the same digit 3 is 75 called a second time no release will take place. The calling subscriber now calls the second digit in the number, which is the digit 3, and the selector is again raised to the third level. This time the switch does 80 not drop back but instead the automatic trunk selecting movement is initiated as usual and an idle trunk is selected which extends to the desired office. This may be the trunk line extending to the second selector F, and when the remaining three digits are called this selector and a connector such as the connector H are operated to complete the connection.

It will be seen from the foregoing that by 100 the use of drop back first selectors one or more offices may be installed without third selectors but with telephone numbers assigned in contemplation of the ultimate use of such third selectors, thus saving a considerable sum of money at the start and at the same time avoiding the necessity of changing the telephone numbers later on. When the size of the office increases and it 105 finally becomes necessary to give service to more than 1000 lines, the trunking system is expanded to full size by the installation of additional switches. These new switches are used as second selectors and replace the 110 selectors, such as the selector F, as terminals of the trunk lines coming from the third level of the first selectors. The present second selectors, such as the selector F, become third selectors and the trunk lines leading thereto will be taken from the third 115 level of the newly installed second selectors. Then another group of third selectors accessible from say the first level of the new second selectors will be installed to take care of the increased growth, and as the 120 office continues to grow still other groups of third selectors may be installed from time to time until all ten of the levels are in use.

The construction of the drop back selec- 125

tors makes it possible to change them readily so that whenever the trunking system in an office is expanded the drop back feature can be eliminated on the level corresponding to such office. This is of course necessary because with the full number of switches installed all the digits in the telephone numbers will have to be used. These drop back selectors can best be understood from a brief 10 description of the operation of one of them in setting up a connection, and such description will now be given, reference being had to the circuit diagram, Fig. 2, which shows the circuits of the drop back selector D, 15 Fig. 1, in detail.

Assuming that the subscriber at substation A is calling the subscriber at substation A', when the receiver is removed the rotary line switch C is operated automatically to establish 20 connection with an idle drop back first selector. Assuming further that the selector D is the switch with which connection is established, the wipers of the line switch will connect with bank contacts 2, 3, and 4, and 25 the calling line will be extended by way of bank contacts 2 and 4, conductors 5 and 7, and normally closed contacts of the switching relay 11 to the line relay 12. The line relay is accordingly energized over the calling 30 subscriber's loop and closes a circuit for the slow acting release relay 13. Upon energizing, relay 13 prepares the selector for operation in its vertical movement at its lower armature, and at its upper armature 35 grounds the release trunk conductor 6. This latter operation renders the trunk line busy and provides a holding circuit for the line switch C in the usual and well understood manner.

40 The calling subscriber may now operate his calling device in accordance with the first digit in the desired number, which is the digit 3. As a result a series of interruptions is produced in the circuit of the line 45 relay 12, and the said relay is deenergized a plurality of times to send a series of impulses through the slow acting relay 15 and the vertical magnet 18. By the operation of the vertical magnet the switch shaft is raised 50 step by step until the wipers 40, 41, and 42 stand opposite the third level of bank contacts. Relay 15 is energized in series with the vertical magnet, maintaining its armature attracted throughout the vertical movement, and at the first upward movement of 55 the shaft, the off normal springs 20 being then closed, this relay closes a circuit for the stepping relay 16. Upon energizing, relay 16 locks itself at its upper armature, 60 and at its lower armature prepares a circuit for the rotary magnet 17.

The shaft having been raised three steps, the outside casing 21 of the cup spring assembly, which is mounted on top of the 65 shaft as shown in the patent to Keith et al.

815,321, March 13, 1906, at b in Fig. 3, engages the projection 23 on spring 22 and springs 24 and 26 are forced into engagement with springs 25 and 27, respectively. The springs 22 and 24 to 27, inclusive, are 70 mounted in any suitable manner on the upper part of the switch frame in such a position that the projection on spring 22 will be engaged, as stated, by the cup spring casing 21 when the shaft is standing at the 75 third level. Now since the vertical impulses have ceased the slow acting relay 15 will deenergize and parallel circuits will be closed simultaneously for the rotary magnet 17 and the release magnet 19. Both circuits 80 include the grounded release trunk conductor 6, which goes to the rotary magnet by way of the contacts of the stepping relay 16, and to the release magnet by way of the switching springs 25 and 24 and the upper 85 contacts of relay 14. The rotary magnet and the release magnet are accordingly both energized at the same time, the former operating to rotate the shaft one step and the latter operating to disengage the double dog 90 from the switch shaft. The rotary magnet also breaks the locking circuit of the stepping relay 16 near the end of its stroke, and the said relay is deenergized. This breaks the rotary magnet circuit and the rotary 95 magnet deenergizes also, with the result that the switch shaft at once drops back and returns to normal position. The restoration of the shaft necessarily follows the deenergization of the rotary magnet because the 100 double dog has been disengaged from the shaft by the release magnet, as previously explained. At the same time that the rotary magnet and release magnet are energized, a circuit is closed by way of springs 27 and 105 26 for the relay 14. Upon energizing, relay 14 locks itself at its lower armature, breaking its initial energizing circuit at the same time, and also opens the circuit of the release magnet at its upper armature. Relay 110 14 is made slightly slow to energize by means of a copper slug so that the release magnet may be fully energized before its circuit is broken.

The selector D is now in normal position 115 so far as its wipers are concerned, and it will be seen that the net result of the calling of the first digit is the locking up of the relay 14. The calling subscriber may now 120 operate his calling device for the next digit, which is also the digit 3. On the second operation the switch shaft is raised by the vertical magnet 18 under control of the line relay 12 just the same as before and the wipers are brought to rest opposite the third 125 level. Relay 15 is energized in series with the vertical magnet when the vertical movement starts and relay 16 is locked up. When the impulses to the vertical magnet cease, relay 15 falls back and as before closes the 130

circuit of the rotary magnet 17. Now, however, since relay 14 is energized, the circuit of the release magnet is not closed. The rotary magnet is energized to rotate the 5 switch wipers one step into engagement with the first set of contacts in the third level, at the same time breaking the circuit of the stepping relay 16. Relay 16 accordingly deenergizes and breaks the circuit of the 10 rotary magnet, which falls back also and again closes its interrupter contact. The operation now depends upon whether the trunk line with which the wipers have connected is busy or is not busy. If the trunk 15 line is busy the test contact with which the test wiper 41 is in engagement will have a ground potential upon it and the stepping relay 16 will again be energized, the rotary magnet circuit will again be closed and the 20 switch wipers will be rotated another step, the stepping relay and magnet being then deenergized as before. This operation will continue as long as test wiper 41 engages grounded or busy test contacts. When the 25 test wiper arrives at a non busy test contact, test contact 44 for example, it will find no ground potential and the stepping relay 16 will not again be energized; but instead the switching relay 11, which has been short circuited heretofore, is energized in series with 30 the said stepping relay over a circuit extending from the grounded release trunk conductor 6 by way of the said relay 11, the interrupter contact of the rotary magnet 17, 35 and the off normal springs 20 to relay 16. Due to the high resistance of relay 11 relay 16 does not operate. Upon energizing, relay 11 connects the release trunk conductor 6 to the test wiper 41; and also extends the 40 line conductors 5 and 7 by way of its upper and lower armatures and their respective working contacts, line wipers 40 and 42, and bank contacts 43 and 45 to trunk conductors 46 and 48.

45 The trunk line comprising conductors 46, 47, and 48 extends to a second selector, such as the selector F, for example, and when the calling line is connected with this trunk line by the operations above described, the line relay of such selector is energized over the calling subscriber's loop. The line relay closes the circuit of the release relay and the latter closes a holding circuit by grounding conductor 47, whereby the switching relay 11 50 of the selector D and the switching relay of the individual line switch are maintained energized after the line and release relays 12 and 13 have fallen back.

55 From this point on the connection is established by operating the selector F and a connector such as the connector H responsive to the calling of the last three digits in the desired number. These operations are well understood and require no further explanation.

It may be stated, in further explanation of the drop back selector, that the spring assembly comprising the springs 22 and 24 to 27, inclusive, is preferably mounted so that it can be adjusted or shifted up and down in accordance with the level on which it is desired that these springs be operated. This is not absolutely necessary, however. Spring 22 is easily removed, and if at any time it is desired to cut out the drop back feature on the level where it is working and change to some other level, the springs corresponding to spring 22 may be removed from all the first selectors and may be replaced by other springs which have the projection located further up or down, as the case may be. It will be understood also that in case there are two offices operating at the same time without third selectors the first selectors will have an additional set of springs mounted similar to the set described except that they are closed on a different level. The two sets of springs are connected in multiple. The cup spring casing 21 being circular in form, as many sets of springs as are required can be accommodated, the various sets being disposed around the casing in the arc of a circle.

Having described my invention what I consider to be new and desire to have protected by Letters Patent will be pointed out in the appended claims.

What I claim is:

1. In a telephone system, a subscriber's line, a series of switches comprising group selectors, hundreds selectors, and connectors directly controllable by the subscriber on said line for connecting with a second line, a second series of switches comprising group selectors, thousands selectors, hundreds selectors, and connectors similarly controlled for connecting with a third line, and automatic telephone numbers assigned to said lines all having the same number of digits.

2. In a telephone system, a subscriber's line, a first selector, means including said first selector, a second selector, and a connector directly controllable by the subscriber on said line for connecting with a second line, means including said first selector, another second selector, a third selector, and another connector similarly controlled for connecting with a third line, telephone numbers for said second and third lines having the same number of digits, and means for automatically releasing said first selector whenever the said second line is called in order to cancel one of the digits in the number.

3. In a telephone system, means including a plurality of serially related directly controlled automatic switches for connecting a calling and called subscriber's line, a different and lesser plurality of similar switches for connecting the said calling line with another called line, a uniform numbering sys-

- tem in which all of the said subscribers have the same number of digits in their telephone numbers, and means for releasing one of the switches used in calling the said second called line when such switch is first operated in order to cancel one of the digits in the number.
4. In a telephone system, a selector switch and means for operating the same, said switch having a primary movement and an automatic secondary selecting movement, a slow acting relay energized during the primary movement and deenergized on the completion thereof to start the secondary movement, a release magnet, and a circuit for said magnet closed by said relay upon deenergizing in case the primary movement has stopped at a certain predetermined point.
5. In a telephone system, a first line, a second line, means including a plurality of serially related directly controlled automatic switches for setting up a connection from said second line to said first line, means including a different number of similar switches for setting up a connection from said first line to said second line, and means for operating said switches according to a uniform numbering arrangement such that said first line and said second line are both called by means of the same number of digits.
6. In a telephone system, a first line, a second line, means including a plurality of serially related directly controlled automatic switches for setting up a connection from any calling line to said first line, means including a smaller number of similar switches for setting up a connection from any calling line to said second line, and means for operating said switches according to a uniform numbering arrangement such that said first line and said second line are both called by means of the same number of digits.
7. In a telephone system, a first line, a second line, means including a plurality of serially related directly controlled automatic trunk selecting switches for setting up a connection from said second line to said first line, means including a different number of similar switches for setting up a connection from said first line to said second line, and means for operating said switches according to a uniform numbering arrangement such that said first line and said second line are both called by means of the same number of digits.
8. In a telephone system, a connector switch and a line accessible thereto, another similar connector and a second line accessible thereto, means including a plurality of serially related directly controlled automatic trunk selecting switches for setting up a connection from any calling line to said first line by way of the first mentioned con-
- nector, means including a different number of similar switches for setting up a connection from any calling line to said second line by way of the second mentioned connector, and means for operating said switches according to a uniform numbering arrangement such that said first line and said second line are both called by means of the same number of digits.
9. In a telephone system, a plurality of lines, a plurality of other lines, means including a plurality of serially related directly controlled automatic switches for setting up a connection from any calling line in either of said pluralities to any line of the first mentioned plurality of lines, means including a smaller number of similar switches for setting up a connection from any calling line in either of said pluralities to any line of said plurality of other lines, and means for operating said switches according to a uniform numbering system such that both called lines are called by means of the same number of digits.
10. In a telephone system, two exchanges, means including a plurality of serially related directly controlled automatic switches for connecting a calling line in either exchange with a called line in the first exchange, means including a smaller number of similar switches for connecting a calling line in either exchange with a called line in the second exchange, and means for operating said switches according to a uniform numbering arrangement such that the lines in one exchange are called by means of the same number of digits as the lines in the other exchange.
11. In a telephone system, a subscriber's line, a first selector, means including said first selector, a second selector, and a connector directly controllable by the subscriber on said line for connecting with a second line, means including said first selector, another second selector, a third selector, and another connector similarly controlled for connecting with a third line, telephone numbers for said second and third lines having the same number of digits, and means in said first selector for automatically cancelling one of the digits in the number whenever said second line is called.
12. In a telephone system, means including a plurality of serially related directly controlled automatic switches for connecting a calling and a called subscriber's line, a different and lesser plurality of similar switches for connecting the said calling line with another called line, a uniform numbering system in which all of the said subscribers have the same number of digits in their telephone numbers, and means in one of the switches used in calling the said second called line for cancelling one of the digits in the number thereof.

13. In a telephone system, means including a plurality of serially related directly controlled automatic switches for connecting a calling and a called subscriber's line, 5 said plurality of switches including a first selector having a single set of wipers, a different and lesser plurality of similar switches for connecting the said calling line with another called line, a uniform numbering system 10 in which all of the said subscribers have the same number of digits in their telephone numbers, and means in the first selector used in calling the said second called line for cancelling one of the digits in the number 15 thereof.
14. In a telephone system, means including a plurality of serially related directly controlled automatic switches for connecting a calling and a called line, said series including 20 a plurality of selectors and a connector, each of said selectors having a single set of wipers, a second series of similar switches for connecting the said calling line with another called line, the said second series including 25 a smaller number of selectors than said first series, a uniform numbering system in which all of the said subscribers have the same number of digits in their telephone numbers, and means in one of the selectors 30 used in calling the said second called line for cancelling one of the digits in the number thereof.
15. In a telephone system, a selector switch and means for operating the same, said switch having a directive primary movement and an automatic secondary selecting movement, means normally effective to start the secondary movement at the end of the primary movement, a release magnet, and adjustable means responsive to the primary movement but effective only at the end thereof for closing a circuit for said release magnet in case the primary movement has stopped at a predetermined point, whereby 40 said switch can be caused to restore at the end of a primary movement of any desired extent.
16. In a telephone system, a switch having a wiper, levels of trunk line terminals of two numerical orders accessible from the 50 said wiper, means for operating the switch in correspondence with the numerical orders, respectively, to select a trunk line of a corresponding numerical order level, and means for barring the switch from seizing a trunk 55 of a selected level of one of said numerical orders if the switch has been selectively operated with respect to such level in accordance with the other numerical order.
17. In a telephone system, a switch, a 60 group of trunks accessible to the wipers of said switch and extending to thousands selectors, a second group of trunk lines accessible to said switch via the same wipers and extending to hundreds selectors, means for 65 operating the switch in accordance with the thousands and hundreds digits of telephone numbers to select said groups, respectively, and means effective to prevent the seizure of a trunk line in case said switch is operated 70 to select the group of trunk lines leading to hundreds selectors responsive to the thousands digit of a number.
18. In a telephone system, an automatic switch, two groups of trunk lines terminating in the bank of said switch, means normally effective to bar access to one of said groups of trunk lines, and means in said switch responsive to a predetermined directive movement thereof for rendering the said 75 group of trunk lines accessible to said switch while also maintaining the other group of trunk lines accessible to said switch.
19. In a telephone system, two groups of trunk lines, an automatic switch normally 80 having access to one of said groups only, means for directly operating and for automatically releasing said switch, and means thereupon effective for rendering the second group of trunk lines accessible to said switch 85 as well as the first group.

Signed by me at Chicago, Cook County, Illinois, this 24th day of June, 1920.

TALBOT G. MARTIN.
